UNITED STATES PATENT OFFICE

2,589,046

CLAW HAMMER WITH EXTENSIBLE
FULCRUMHarvey H. Brown and Bert Ned Reed, Mountain
City, Nev., assignors to Nailmaster, Inc., a cor-
poration of Nevada

Application July 5, 1949, Serial No. 103,146

4 Claims. (Cl. 254—26)

1

This invention relates generally to hammers and more particularly to a claw hammer having an extensible fulcrum member manually extended when desired by the user and normally biased into retracted position flush with the exterior surface of the hammer head.

A primary object of this invention is to provide a fulcrum member which may be extended whenever necessary to facilitate the drawing of longer nails after such longer nails have been partially extracted.

Another object of this invention is to provide a hammer having a head with claws for engaging the head of a nail, an extensible fulcrum member and means for securing a handle in the head, the parts of the head being so arranged and designed to facilitate assembly as well as use of the hammer.

Another object of this invention is to provide a hammer head which has an extensible fulcrum member but which can be used in the normal manner with the fulcrum member fully retracted and in no way interfering with such normal use.

And a last object to be mentioned specifically is to provide a device for the mentioned character which is relatively inexpensive and completely practicable to manufacture, which is safe, simple and convenient to use, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is an elevational view of a hammer with this invention operatively applied therein, portions of the handle and head being broken away to facilitate the illustration of the construction thereof, the fulcrum member and associated parts being shown in dash line in a second position, this second position being that in which the fulcrum member is extended for use;

Figure 2 is a vertical sectional view, taken substantially upon the line 2—2 in Figure 1, and looking in the direction of the arrows;

Figure 3 is a transverse sectional view, taken substantially on the line 3—3 in Figure 1;

Figure 4 is an enlarged three dimensional view of the fulcrum member including a portion of the shank thereof;

Figure 5 is a side elevational view, on a re-

2

duced scale, showing a hammer head with this invention operatively applied therein and a portion of the hammer handle, portions of the fulcrum member being broken away to facilitate the illustration of the form of recess in the head used to accommodate the fulcrum member when in retracted position; and

Figure 6 is a side elevational view of the claw hammer with the fulcrum extended, the figure being designed to show how the invention is used.

Similar characters of reference designate similar or identical elements and portions throughout the specification and throughout the 15 different views in the drawing.

Referring now to the drawing in detail, this claw hammer includes a head 10 having a handle receiving socket 12, to receive the end 14 of the hammer handle 16.

20 The hammer head is provided with a fulcrum member, generally indicated at 24 and comprised of an end portion 26, and lateral arms 28, the general configuration of the fulcrum member being U-shaped, the end member 26 being rounded on its outer surface and extending beyond the corresponding edges of the arms 28 both on the sides thereof parallel the arms and at the ends 30. A recess is formed in the head to accommodate the fulcrum member 24, and it should be carefully noted that this recess has portions indicated at 32 to accommodate the end member 26 with its extending end portions 30, this end recess 32 being continued into two lateral recesses 34 on the sides of the head 10, the lateral recesses being dimensioned to receive the lateral arms 28 of the fulcrum member when the same is in retracted position.

25 A centrally disposed shank 36 is integrally secured to the inner surface of the end portion 26 of the fulcrum member, and this shank has a helical spring 38 associated coaxially therewith and compressed between a wall 40 positioned between the handle receiving socket 12 and the above described recess in the head and a nut threaded as indicated at 42 on the end of the shank 36 remote from the end portion 26. The handle will be provided with a bore 44 to receive the shank 36, spring 38 and nut 42, and the wall 40 will, of course, be apertured as indicated at 46, to allow the shank to pass therethrough without undue friction.

30 In order to provide a simple and effective fulcrum construction, the head has been designed with special means for securing the end 14 of the handle therein. This special means utilizes some

of the structure already described in connection with the provision of the extensible fulcrum in the head, and the wall 40 is provided with cuneiform members 48 having the sharpened ends thereof extending into the end 14 of the handle, to spread the same into tight engagement within the handle receiving socket 12.

The operation of this invention will be clearly understood from a consideration of the foregoing description of the mechanical details thereof, taken in connection with the drawing and the above recitation of the objects of this invention. In recapitulation, it may be further noted that when a nail such as that indicated at 50 has been partially withdrawn, the fulcrum member 24 can be extended manually by pulling the same outwardly against the action of the spring 38 and rotating the fulcrum member through 90° about the shank 36 as axis and allowing the lateral arms 28 to seat onto the head with the said arms in terminal engagement with portions of the head extending transversely thereof between the lateral recesses 34. When the nail has been withdrawn and it is desired to again use the hammer in the ordinary manner, the fulcrum member 24 is rotated in either direction through 90° and the spring 38 is allowed to retract the fulcrum member.

It will be clear that all of the objects recited above are amply achieved by this invention, and further description would appear unnecessary. Minor variation from the embodiment disclosed in the drawing may be resorted to without departure from the spirit of this invention.

Having described the invention, what is claimed as new is:

11. A claw hammer having a head and a handle, one end of said handle having a bore, said head having a socket on one side thereof to receive said one end and an end recess in the head on one side thereof opposite said socket, said head having an apertured wall between said recess and said socket, cuneiform members on said wall having the sharpened ends extending into said socket to spread said end of the handle into tight engagement with the head, a fulcrum member having a portion thereof seated in retracted position in said recess and having a shank extending through

said aperture in said wall into said bore, retaining means for said fulcrum member in an alternative extended position, and means to bias said shank and fulcrum member into retracted position.

5 2. A hammer according to claim 1 and wherein said last mentioned means is a coiled spring arranged coaxially of said shank within said bore and compressed between said wall and a portion of said shank.

10 3. A hammer according to claim 1 and wherein said head has lateral recesses extending into said end recess, said fulcrum member being rotatable about its longitudinal shank axis having lateral 15 arms seated in said lateral recesses when the fulcrum member is in retracted position, said retaining means comprising said lateral arms which terminally engage the head when the fulcrum member is withdrawn and rotated through ninety degrees into said extended position.

20 4. A claw hammer having a head and a handle, one end of said handle having a bore, said head having a socket on one side thereof to receive one end and an end recess in the head on the 25 side thereof opposite said socket, said head having an apertured wall between said recess and said socket, a fulcrum member having a portion thereof seated in retracted position in said recess and having a shank extending through said aperture 30 in said wall into said bore, retaining means for said fulcrum in an alternative extended position, and means to bias said shank and fulcrum member into retracted position.
